UNITED STATES PATENT OFFICE.

JASPER STANLEY WINGET, OF YORK, PENNSYLVANIA.

CIGAR-BUNCHING MACHINE.

1,321,692.

Specification of Letters Patent. Patented Nov. 11, 1919.

Application filed March 20, 1919. Serial No. 283,928.

To all whom it may concern:

Be it known that I, JASPER STANLEY WINGET, a citizen of the United States, residing at York, in the county of York and State of Pennsylvania, have invented certain new and useful Improvements in Cigar-Bunching Machines, of which the following is a specification, reference being had therein to the accompanying drawing.

10 This invention relates to improvements in cigar bunching machines, and is of the hand-operated type in which there is a bed plate, an apron adapted to be formed into substantially a U-shape fold in a pocket receiving space to receive the bunch to be rolled, and a roll carrying mechanism which rolls the bunch in the loop or pocket as it is moved across the face of the bed-plate.

15 The object of my invention is to provide this type of machine with means for taking up or tightening the apron as it moves across the bed-plate for the purpose of reducing the size of the apron pocket as the bunch is being compressed, until it has reached its 20 proper size.

Other objects of my present invention will appear from the following description.

In the accompanying drawings—

25 Figure 1 is a vertical central longitudinal 30 sectional view, on the line 1—1 of Fig. 2.

Fig. 2 is a top plan view of my improved machine.

Fig. 3 is a disassembled perspective view of the parts which comprise my present take-up or tightening improvement.

Fig. 4 is a perspective view showing a modification in the construction of the tightening or take-up device.

35 In carrying out my invention, the machine is provided with a rectangular base-frame 1, which is adapted to be secured to any suitable support or table 2.

40 A bed-plate 3 is supported in an elevated position by the standard 4, at its rear end 45 which projects upward and inward at a slight angle, and two upwardly projecting arms 5, which project upwardly from two arms 6, which project downwardly from the base-frame 1, and the arms 6, 5 and 4 50 are preferably integral with the bed-plate 3 and base-frame 1. Projecting downwardly from the opposite or rear end of the base-frame 1, are two standards 7, between which is pivoted a swinging frame 8 at the point 55 9. A roller 10 is journaled between the upper ends 11 of the frame 8 and in a plane

above the bed-plate 3. Projecting from one of the upper ends 11, of the frame 8, is a handle 12, for swinging the frame 8 back and forth.

60 An apron 13 has its rear end 14 attached to the upper end of the arm 4, and its front end 15 is attached to a roller 16, which is journaled between two arms 17, which project upwardly from the front end of the 65 base-frame 1. This roller 16 has at one end a ratchet wheel 18, which is adapted to engage a suitable pin or stop 19, projecting from the adjacent arm 17, while the opposite end of the roller 16 projects and carries 70 a spring 20 between a nut 21 and the arm 17, which serves to hold the ratchet 18 normally in engagement with the stop 19. By this arrangement the apron 13 can be tightened or loosened according to the size of the 75 bunch to be rolled.

80 As is understood by those skilled in this art, in this type of machine the apron 13 extends down into a loop or pocket, as shown in dotted lines 22, and that filler to be 85 formed into a bunch is placed in this pocket. This pocket is formed in what may be termed a pocket forming space 23, between the front end 24 of the bedplate 3 and the front end of the base-frame 1. The bunch 85 is then rolled in the ordinary machine of this type by swinging the frame 8 from the position shown in dotted lines at the front end of the machine to the position shown in dotted lines at the rear end of the machine, 90 the bunch 25 being rolled in the loop or pocket of the apron as the frame 8 with its roller 10 is swung over the bed-plate, and when the swing of the frame is completed, the rolled bunch will fall out of the pocket 95 as shown at 26, and may be caught in the hand or any desired receptacle.

100 When a machine of this type is being used for putting on the wrapper as well as for rolling the bunch, the wrapper or binder is laid on the apron diagonally across it with one end well down in the pocket. The loose filler is then placed in the pocket and as the frame 8 is swung, as just described, the loose filler or bunch is rolled with the 105 binder therearound in the manner just described.

110 My present improvement is to provide an automatic tightening or take-up mechanism for the apron, whereby it is shortened for a predetermined distance during the rolling and compressing the filler or bunch to re-

duce the size of the apron pocket or loop corresponding to the reduced size of the filler or bunch as it is rolled and compressed. I will now describe this improved tightening or take-up mechanism.

My improved take-up mechanism comprises a U-shaped frame or member A, which comprises two end arms 27, and a bar or connecting arm 28, which are journaled on the roller 16 adjacent the two arms 17, which project upwardly from the base frame 1. The connecting arm 28 of this U-shaped frame is under the apron 13 and this frame is swung in an outward direction to tighten the apron as the frame 8 is swung over the bed-plate 3, by the following mechanism: Preferably, two bell-crank shaped levers B are pivoted to the inner sides of the downwardly projecting arms 6 at the points 29. The upwardly projecting arms 30 of these bell-crank levers B are connected with the lower ends of the arms 27 of the U-shaped frame A by links 31, which have their outer ends pivoted to the lower ends of the arms 27 at 32, and their inner ends pivoted to the arms 30 of the bell-crank levers at the points 33. The other ends 34 of the bell crank levers are provided with slotted arms 35. Passing through the slots 36 of the arms 35 and into the side arms of the frame 8, are suitable pins 37 around which preferably are placed loose sleeves 38. These slots 36 are formed for a part of their length eccentric to the pivotal points 9 of the frame 8, so that as the frame 8 is moved from the front to the rear end of the machine, the bell-crank levers B are moved from the position shown in dotted lines Fig. 1, to the position shown in solid lines, thus swinging the arms 30 inward and tilting the U-shaped frame A outward to the position shown in Fig. 1, and drawing the apron in that same direction, thus tightening it and reducing the size of the bunch containing loop of the apron as the bunch is being rolled and compressed, as will be readily understood. I am aware that it is not new to provide a take-up or tightening device for the apron 50 of a cigar bunch rolling machine, but I do not know of any that are constructed like mine, or that operate in the same way.

While I have shown two bell-crank levers B, I desire it to be understood that a single bell-crank lever could be used for tightening the U-shaped frame A, if made sufficiently strong to prevent it from twisting when operated from one end only. By using two of the bell-crank levers, as here shown, the parts can be made lighter, because the tilt and tightening strain on the U-shaped frame A will be the same at each end and have no tendency to twist the frame.

In Fig. 4, I show a modification of my take-up device, in that the slots in the arms

35 are made zigzag in shape, as shown at 36', by means of which the U-shaped frame 28 is given a vibrating motion as the roller 10 is passing over the bed-plate. This form of slot will impart to the bunch being rolled 70 the hand roller effect, if such effect is desired. However, a more uniform effect is obtained by the straight slot, but when desired the hand-made effect can be obtained by the zigzag slot which gives a variation 75 in the pressure on the bunch being rolled like the hand rolling, and produces substantially the same effect and result.

Having thus described my invention, what I claim and desire to secure by Letters Pat- 80 ent is:

1. A cigar-bunch rolling machine of the type described, comprising a bed-plate, an apron, a swinging frame carrying a roller extending across the bed plate for the purpose described, an apron pocket spaced at the front end of the bed-plate, a swinging take-up member at the outer side of the pocket space, independent of the apron ends and engaging the apron between its ends, a 90 bell crank lever having one end operatively connected with the swinging frame and its opposite end with the take-up device whereby the swinging of the frame over the bed-plate to roll the bunch automatically moves 95 the take-up device in the opposite direction, for the purpose of tightening the apron.

2. A cigar bunch rolling machine comprising a bed-plate, an apron coöperating therewith, a swinging frame having its free 100 end provided with a roller projecting across the bed-plate and the apron, an apron pocket space at the front end of the bed plate, a U-shaped swinging take-up frame located at the outer side of the pocket space and en- 105 gaging the under side of the apron between its ends, a bell-crank lever having one end connected with the U-shaped take-up frame and its opposite end operatively connected with the swinging frame, whereby the move- 110 ment of the swinging frame to roll the bunch causes the U-shaped tightening device to move in the opposite direction and tighten the apron by pushing it out between its ends.

3. A cigar bunch rolling machine, comprising a bed-plate, an apron coöperating therewith, a swinging frame having one end pivoted below the bed-plate and its free end carrying a roller above the bed-plate, the 120 ends of the apron suitably attached, a U-shaped swinging take-up device located under and engaging the front end of the apron and at a point inside of its adjacent attached end, a bell crank lever having one end operatively connected with the take-up device and its opposite end provided with a slot eccentrically arranged relative to the pivot of the swinging frame, and a stud carried by the swinging frame and passing through the 125 130

slot whereby the movement of the frame to roll the bunch swings the take-up device in the opposite direction to tighten the apron.

4. A cigar bunch rolling machine, comprising a bed-plate, an apron coöperating therewith, a swinging frame pivoted below the bed-plate and its free end extending above the bed-plate carrying a roller, a take-up device movable independently of the 10 apron and pivoted and having one swinging end engaging the under side of the apron adjacent its front end, a bell-crank lever pivoted below the take-up device having one end connected with the opposite swinging 15 end of the take up device and its opposite end provided with a slot arranged eccentrically to the pivotal point of the swinging frame, a stud projecting from the swinging frame and passing through the slot whereby 20 the movement of the swinging frame to roll the bunch swings that part of the take-up device under the apron in the opposite direction, for the purpose described.

5. A cigar bunch rolling machine comprising a bed-plate, an apron coöperating therewith, a swinging frame pivoted below the bed-plate with its free end extending above the bed-plate and carrying a roller, an apron pocket at the front end of the bed-plate, a U-shaped take-up device having its 30 ends intermediately pivoted with its longitudinal portion under the apron near its front end, two bell-crank levers pivoted below the take-up device, the bell-crank levers 35 having one of their ends connected respectively with the lower ends of the U-shaped take-up device, the other ends of the bell-crank levers having slots eccentrically ar-

ranged to the pivotal point of the swinging frame and studs projecting from the swinging frame into the slots whereby the movement of the swinging frame to roll the bunch swings the longitudinal portion of the take-up device in the opposite direction to tighten 40 the apron.

6. A cigar bunch rolling machine, comprising a bed-plate, an apron coöperating therewith, a swinging take-up device operatively connected with the apron, a swinging frame pivoted below the bed-plate and carrying a roller coöperating with the apron above the bed plate as described, and an operating mechanism between the swinging frame and the take-up device imparting to the latter an intermittent tightening and 55 loosening action on the take-up device for the purpose described.

7. In a construction such as set forth in claim 1, the slot of the bell-crank having a zigzag formation for the purpose described. 60

8. A cigar bunch rolling machine comprising a bed-plate, an apron coöperating therewith, a swinging frame carrying a roller coöperating with the apron above the bed-plate, means arranged to take up the 65 apron as the swinging frame roller coöperates with the apron, and an operating connection between the take-up means and the swinging frame, said operating connection having a zigzag operating surface to impart 70 to the apron an intermittent tightening and loosening action for the purpose described.

In testimony whereof I hereunto affix my signature.

JASPER STANLEY WINGET.
